(57) **CLAIM**

The ornamental design for an electrical connector, as shown and described.

DESCRIPTION

FIG. 1 is a front elevational view of an electrical connector showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a cross-sectional view showing the electrical connector of FIG. 1, taken along lines VII—VII;

FIG. 8 a front, top and right side perspective view thereof;

FIG. 9 is a rear, right and bottom side perspective view thereof;

FIG. 10 is an enlarged view showing the electrical connector of FIG. 4; and,

FIG. 11 is an enlarged view showing the electrical connector of FIG. 7.
